UNITED STATES PATENT OFFICE.

DE WITT C. SEE, OF MECHANICSVILLE, NEW YORK.

DESIGN FOR AN EYELET.

SPECIFICATION forming part of Design No. 30,465, dated April 4, 1899.

Application filed March 19, 1898. Serial No. 674,533. Term of patent 14 years.

To all whom it may concern:

Be it known that I, DE WITT C. SEE, a citizen of the United States, residing at Mechanicville, in the county of Saratoga and State of New York, have invented and produced a new and original Design for Eyelets, of which the following is a specification, reference being had to the accompanying drawings, forming a part thereof.

10 Figure 1 is a plan view of my invention. Fig. 2 is a vertical cross-sectional view on the line *a a* of Fig. 1.

Like letters of reference denote corresponding parts in each of the views.

15 My invention consists of an oval frame *E*, having a curved flange *e* at its upper or outer

edge. The sides of the eyelet are in form of a compound curve and are wider apart at the top than at the bottom, as indicated in Fig. 2.

The eyelet is provided with a shaft or bearing *A*, having flaring ends *C*.

Having described my invention, what I claim as new, and desire to secure by Letters Patent, is—

The design for an eyelet, as herein shown 25 and described.

In testimony whereof I affix my signature in the presence of two witnesses.

DE WITT C. SEE.

Witnesses:

J. C. REYNOLDS,
L. W. NELSON.
